INTERCHANGEABLE BLADED SCREW
DRIVER

Joseph K. Roff, Brooklyn, N. Y., assignor of one-third to William L. Roff and one-third to Adolf Paul, both of Brooklyn, N. Y.

Application March 8, 1933. Serial No. 660,022

6 Claims. (Cl. 145—50)

This invention relates to screw drivers or that class of tools used by artisans in entering and removing ordinary screws for wood or metal.

One of the objects is to provide a screw driver comprising a shank having its end blades fitted to the nicks or slots of screws of different sizes and which is easily and quickly reversed so as to bring the proper blade into position for operation.

A further feature is in the provision of means for securing the screw driver shank, with either end extended, as firmly and rigidly as if the shank was set directly into the handle.

Another purpose is to produce an interchangeable bladed screw driver possessing the foregoing advantages, providing an efficient tool of pleasing appearance, at a moderate cost.

These advantageous objects are accomplished by the novel construction and combination of parts hereinafter described and illustrated in the accompanying drawing, forming material component of this disclosure, and in which:—

Figure 1 is a perspective view of an implement made in accordance with the invention.

Figure 2 is a similar view of the operative inner element thereof.

Figure 3 is a perspective view of the handle and sleeve engaged therein.

Figure 4 is a like view of the sleeve in detail.

Figure 5 is a longitudinal sectional view of the implement, taken on line 5—5 of Figure 1.

Figure 6 is a fragmentary longitudinal sectional view of the tool shank and parts carried by it.

Figure 7 is a transverse sectional view taken on line 7—7 of Figure 5.

Figure 8 is a similar sectional view taken on line 8—8 of Figure 5.

Figure 9 is another like sectional view taken on line 9—9 of Figure 5.

Figure 10 is a transverse sectional view, similar to Figure 8, but showing a modification in construction.

Referring in detail to the drawing a handle 10 of conventional type is provided with an axial bore 11 at its front end, terminating in a shoulder 12 beyond which is reduced opening 13, extending well into the main part of the handle, which is further provided with the usual ferrule 14.

The shank 15 of the screw driver is formed with differently sized blades, respectively 16 and 18' and midway in the length of the shank is a longitudinally knurled or ribbed portion 17, in one side of which, centrally in its length, is a conical recess 18.

Forced over the shank and tight fitted to the raised ribs 17 is an elongated collar 19 in which is fixed a screw-threaded stud 20, its point entering the recess 18 while its body extends laterally outward to receive a thumb nut 21, provided with a convex inner side 21' and retained on the stud by reason of upsetting its outer extremity.

The collar 19 slidably fitted to engage in a tubular sleeve 22 having its central portion longitudinally knurled, as at 23, and adapted to be forcibly pressed into the socket bore 11 in the handle, and at the end of the sleeve 22 are spaced longitudinal extending prongs 24 of dovetailed cross section which are forced into the material 70 of the handle at the shouldered bottom 12 of the bore 11.

The sleeve 22 when forced into the handle, tends to condense its wooden fibers by the pressure exerted, within the limits of the ferrule 14.

In the outer extending end of the sleeve 22 is a slot 25 adapted to engage the body of the stud 20 and the sleeve at both sides of the slot, is concavely formed to receive the corresponding portion 21' of the nut when manually turned to engage therein, thus locking the shank of the double ended screw driver in either of its adjusted positions.

The seat 26 receives the nut securely, thereby retaining the tool shank in either of its adjusted positions and also permits other tools similarly provided with collars, studs and nuts to be substituted at will.

As indicated in Figure 10, the shank of the implement may be polygonal as at 15', on which 90 is secured a ferrule 19' by electric welding or other effective means, and the sleeve 22' is used without prongs or knurling wherein it differs from the sleeve shown in Figure 4.

It will be apparent that the device, as described, is applicable to types of tools other than a screw driver, and it will be understood that modifications in sizes, proportions, and minor details of construction may be resorted to without confliction with the appended claims.

Having thus described the invention what is claimed as new and what I desire to secure by Letters Patent is:—

1. A screw driver comprising a handle having 105 an axial bore ending in a shoulder and a hollow chamber therebeyond, a sleeve tight fitted to said bore, prongs having parallel edges extending in spaced relation from the inner end of said sleeve, said prongs being forced into said 110

- shoulder, means on said sleeve to prevent rotation in said bore, said sleeve having a longitudinal slot in its outer end, a shank having different sized blade nibs on its opposite ends, said shank being knurled at its central portion and provided with a notch, a collar forced over the knurled portion, a screw stud set in said collar, the inner end of said stud engaging in said notch, said stud being receivable in the slot of said sleeve when the collar is entered therein, a thumb nut on said stud to clamp said sleeve, and means to retain said nut on the sleeve, either of said blade nibs being entrable within said chamber when the other is operatively extended.
- 15 2. A screw driver comprising a ferruled handle having an axial bore with a counterbore in the ferrule carrying portion, a sleeve having a knurled portion forced into the counterbore, straight prongs on the inner end of said sleeve embedded in the bottom of said counterbore, a concave seat on said sleeve adjacent its outer end, said seat having a central longitudinal slot, a driver shank having relatively large and small blade nibs at its opposite ends, a collar fixed centrally on said shank, a threaded stud fixed in said collar to impinge on said shank, said collar being fitted to engage in said sleeve, a thumb-nut on said stud having a part to clamp against said seat and means on said stud to prevent complete separation of said nut.
- 25 3. A screw driver comprising a ferruled handle having an axial bore of relatively large and small diameters, a sleeve, knurled and pronged to rigidly engage in the larger bore, said sleeve

having a slot in its outer end, a double ended driver shank having a central collar suited to engage in said sleeve, a stud fixed in said collar to engage said sleeve, a manually operable nut threaded on said stud, and co-operative means on said nut and sleeve whereby they may be firmly clamped together.

4. A screw driver comprising a ferruled handle having an axial bore of relatively large and small diameters, a knurled sleeve fixedly engaged in the larger bore, a double ended driver shank having a fixed central collar fitting said sleeve, a threaded radial stud in said collar, means in the outer end of said sleeve to receive said stud, and a clamping means carried by said stud to engage said sleeve.

5. A tool handle having aligned communicating bores of relatively different diameters the lesser bore being innermost, and a sleeve rigidly fixed in the outer bore, said sleeve having a concave seat and a longitudinal slot passing therethrough.

6. In combination, a tool handle having a blade receiving socket, a sleeve fixed in said socket and extending outwardly therebeyond, said sleeve having a longitudinal slot in its outer end, a reversible shank having blades to pass through said sleeve in entering the socket, a collar fixed centrally on said shank, a threaded post extending radially from said collar to enter the slot in said sleeve, said post having a head, and a nut carried by said post below said head to engage said sleeve at the edges of said slot.
